US00D619795S

(12) **United States Design Patent**
McBride

(10) **Patent No.:** **US D619,795 S**
(45) **Date of Patent:** **** Jul. 20, 2010**

(54) **ACCESSORY STRIP**

(75) Inventor: **Louise McBride**, Potts Point (AU)

(73) Assignee: **Shoo Sticks Pty Limited**, Potts Point, NSW (AU)

(**) Term: **14 Years**

(21) Appl. No.: **29/277,952**

(22) Filed: **Mar. 14, 2007**

(30) **Foreign Application Priority Data**

Sep. 14, 2006 (AU) 14126/2006

(51) **LOC (9) Cl.** **02-04**

(52) **U.S. Cl.** **D2/961; D2/946**

(58) **Field of Classification Search** ..... D2/896, D2/943, 946, 947, 948, 949, 950, 954, 956, D2/961, 968, 976, 977, 978; 36/113, 114, 36/115, 136, 137, 138, 7.1 A, 73; D24/135, D24/136, 155, 189, 190; D28/42, 56, 57, D28/59; 602/41, 42, 52, 54, 57, 58, 79, 903; 128/200.24; 294/5.5

(57) **CLAIM**

The ornamental design for an accessory strip, as shown and described.

DESCRIPTION

FIG. 1 is a front perspective view of an accessory strip showing my new design;

FIG. 2 is a front perspective view of the accessory strip of FIG. 1 with the strip partially peeled off;

FIG. 3 is a top view of an accessory strip shown in FIG. 1;

FIG. 4 is a side view of an accessory strip shown in FIG. 1; FIG. 5 is an end view of an accessory strip shown in FIG. 1; and,

FIG. 6 is another end view of an accessory strip shown in FIG. 1.

All sides not shown in the drawings form no part of the claimed design.
